UNITED STATES PATENT OFFICE.

WILLIAM L. HART AND FRANK J. DANIELS, OF OLNEY, ILLINOIS; SAID HART ASSIGNOR
TO CHARLES C. DANIELS, OF OLNEY, ILLINOIS.

MOLD.

No. 867,129.

Specification of Letters Patent.

Patented Sept. 24, 1907.

Application filed December 1, 1906. Serial No. 345,904.

To all whom it may concern:

Be it known that we, WILLIAM L. HART and FRANK J. DANIELS, citizens of the United States, residing at Olney, in the county of Richland and State of Illinois, 5 have invented new and useful Improvements in Molds, of which the following is a specification.

This invention relates to molds of the type employed for producing cement or other artificial stone building blocks of hollow formation, and embodies a frame in 10 which the mold walls are movably mounted and which is in turn removably arranged on a base plate with which the cores employed in the mold are detachably engaged.

The invention has for its objects to provide a comparatively simple, inexpensive device of this character 15 wherein the mold walls may be readily moved to or from casting position, one in which the mold may be conveniently removed from the completed block, and this without injuring the latter, and one in which the cores will be firmly and securely retained in position 20 on the base or pallet during the formation of the block and be quickly released at the completion of the casting operation, the initial step in the action of releasing the cores serving to positively move the same out of the 25 cast block.

With these and other objects in view, the invention comprises the novel features of construction and combination of parts more fully hereinafter described.

In the accompanying drawings, Figure 1 is a top plan 30 view of a mold embodying the invention, showing the parts in casting position and a completed block within the mold. Fig. 2 is a vertical section taken centrally and longitudinally through the mold on the line 2—2 of Fig. 1. Fig. 3 is a vertical transverse section taken 35 on the line 3—3 of Fig. 1, and showing in dotted lines the manner of removing the mold from the block. Fig. 4 is a detail perspective view of one of the pivoting members or links. Fig. 5 is a perspective view of the lock plate.

40 Referring to the drawings, it will be seen that the mold, which rests on a base plate or pallet 1, comprises a front wall 2, end walls 3, and a rear side wall 4, there being formed on the upper edges of the wall outturned portions or flanges 5 conjointly forming a flaring mouth 45 through the medium of which the material may be readily introduced into the mold, while arranged on the base or pallet 1 is a lock member or strip 6 made of metal and provided at points adjacent its ends with depending internally threaded tubular thimbles 7 de- 50 signed to seat and fit tightly within openings 8 formed through the base plate 1.

The mold is mounted in a frame 9 preferably composed of metal tubing and of open rectangular form, as shown, comprising longitudinal side bars or rails 10—11 and end bars or rails 12 terminally joined to the rails

10—11 by means of coupling members or elbows 13 having at their inner sides horizontal webs 14 perforated to receive vertical end posts 15 secured in place in the frame by means of nuts 16 tapped on to their upper ends and resting at their lower ends on the base 1. 60

The front wall 2 of the mold is fixedly attached to the front rails 10 by means of rivets or other attaching members 17, while the end walls 3 and rear wall 4 are movably supported in the frame through the medium of connecting arms or links 18 pivoted at their outer ends by 65 means of pintles 19 to ears 20 formed on clips 21 suitably fixed on the frame members 11—12 and are pivoted at their inner ends by means of pintles 22 to bracket plates 23, riveted or otherwise secured to the mold walls, it being noted that there are employed a plurality of 70 connecting links which are identical in form and are disposed at appropriately spaced intervals and further, that the movable walls will, when carried to inactive position, be moved upwardly and outwardly through the medium of the links 18 for a purpose which will 75 hereinafter appear.

Arranged in the mold and for forming transverse air openings through the block 24, is a pair of tubular metal cores 25 of gradually diminishing taper from their upper to their lower ends and preferably of rectangular form in cross section, as shown, there being fixed in each of the cores and respectively adjacent its ends a pair of horizontal transverse bracing pieces or straps 26, suitably perforated to receive a central longitudinal rotary locking member or rod 27 having at its upper end 80 a hand-piece 28, and terminating at its lower end in an enlarged, externally threaded engaging portion or head 29, adapted to be screwed into one of the thimbles 7 and to bear at its upper end against the lower strap 26, while fixed on the rod 27 and to bear on the upper bracing strap 26, is a collar 30 which, together with the head 29, secures the rod against longitudinal movement relative to the core. 85

In practice, the frame 9 carrying the mold, is properly positioned on the base-plate or pallet 1, and with the 90 mold walls arranged in casting position, as in Figs. 1 and 2, after which the cores 25 are fixedly arranged in the mold by entering the engaging portions 29 of the locking rods into the thimbles 7, in which operation the end-pieces 28 are grasped and the rods suitably rotated. 95 After the mold and cores have been properly positioned the mold is filled with plastic material for forming the block 24, and after the material has set, the cores are released from the pallet 1 for removal by rotating the rods 27 to disengage the heads 29 from the lock-plate 6, 100 it being noted in this connection that in the operation of releasing the cores and, owing to the rods 27 being held against longitudinal movement relative to the cores, the latter will be positively moved upward a sufficient distance to wholly free them from the block, 105 110

after which they may be readily lifted out of the mold, and this without injuring the block. The cores having been removed, the mold walls 3 and 4 are moved to inactive position for releasing the block by swinging the 5 arms 18 upward on their pivots 19, whereby an upward and outward movement is imparted to the walls, thus carrying them away from and without injury to the adjacent faces of the block. After the walls 3 and 4 have reached the limit of their outward movement, the frame 10 9 is tilted bodily forward, as seen by dotted lines in Fig. 3, thus moving the wall 2 away from the front face of the block, which is thus wholly freed from the mold and remains standing on the pallet 1 for removal to the drying shed. It is to be particularly observed that the 15 mold walls may be conveniently arranged in casting or non-casting position and that in the operation of releasing the completed block, the walls will be moved diagonally away from the faces of the latter, whereby mar-ring of the block is obviated.

20 Having thus described the invention, what I claim is:—

1. In a device of the class described, a frame, a mold disposed therein comprising side and end walls, one of said walls being fixed to the frame and the others movably 25 arranged therein, a pallet on which the mold rests, and means connecting the movable walls to the frame for upward and outward swinging movement to inactive position, the mold being adapted after the movable walls have been moved to inactive position, to tip bodily forward for dis-30 charging the block.

2. In a device of the class described, a frame, a mold arranged therein and comprising side and end walls, one of said walls being fixed to the frame and the others being movably sustained therein, connecting arms pivoted in the

frame and to the movable walls for carrying the latter, 35 and a pallet on which the mold rests, the movable walls being adapted to swing upward and outward to inactive position and the mold arranged to dip bodily forward in discharging the block.

3. In a device of the class described, the combination of 40 a flat mold base, a tilttable frame normally resting on the base, a mold comprising sides, one of which is attached to the frame to tilt therewith and the others movable independently of the frame, and parallel links connected with and disposed between each independently movable side and 45 adjacent portion of the frame.

4. In a device of the class described, the combination of 40 a flat mold base, a tilttable frame normally resting on the top thereof, a mold normally resting on the top of the base and having one side attached to the frame to tilt therewith and its remaining sides spaced from the frame, and links connecting the spaced sides with the mold for independent movement and adapted when in horizontal position to hold the sides in operative relation.

5. In a device of the class described, a mold, a mold 55 base provided with a plurality of spaced and connected internally threaded keeper openings, a plurality of hollow cores removably arranged in the mold, fixed braces ex-60 tended transversely of the cores and having bearing openings, a rotary locking rod for each core journaled in said openings and provided with a threaded engaging portion designed for threaded engagement with the adjacent keeper opening to detachably secure the core in place, and means on each rod for engagement with the braces to fix the rod against longitudinal movement relative to the core. 65

In testimony whereof, we affix our signatures in presence of two witnesses.

WILLIAM L. HART.
FRANK J. DANIELS.
